(57) **CLAIM**

The ornamental design for an outsole for a shoe, as shown and described.

DESCRIPTION

FIG. 1 is a perspective view of an outsole for a shoe in accordance with my new design;

FIG. 2 is a bottom view thereof;

FIG. 3 is a right view thereof;

FIG. 4 is a left view thereof;

FIG. 5 is a front view thereof; and,

FIG. 6 is a rear view thereof.

The broken lines shown in all of the figures are for environmental purposes and form no part of the claim.

1 Claim, 6 Drawing Sheets---
